(57) **CLAIM**

The ornamental design for a “display with graphical user interface”, as shown and described.

DESCRIPTION

The sole FIGURE is a front view of a display with graphical user interface showing our new design.

As indicated in the title, the article of manufacture to which the ornamental design has been applied is a “display with graphical user interface.” The outer edge of the display is understood to be congruent with the outer edge of the graphical interface.

1 Claim, 1 Drawing Sheet
